UNITED STATES PATENT OFFICE.

JAMES F. McBIRNEY, OF HARTFORD, CONNECTICUT, ASSIGNOR TO ROYAL TYPEWRITER COMPANY, OF NEW YORK, N. Y., A CORPORATION OF NEW JERSEY.

TYPE-WRITING MACHINE.

984,284.

Specification of Letters Patent. Patented Feb. 14, 1911.

Application filed October 21, 1909. Serial No. 523,847.

To all whom it may concern:

Be it known that I, JAMES F. McBIRNEY, a citizen of the United States of America, residing in Hartford, county of Hartford, 5 and State of Connecticut, have invented certain Improvements in Type-Writing Machines, of which the following is a specification.

This invention relates to means for locking the shifting platen or carriage in a typewriting machine in lower case position and supporting it in upper case position, both functions being performed by a pivoted latch.

15 The invention is an improvement upon the construction disclosed in Letters Patent to Edward B. Hess, No. 858,179 dated June 25, 1907. As in that patent, the invention is shown applied to the Royal Standard machine manufactured by the Royal Typewriter Company.

In the accompanying drawings: Figure 1 is a longitudinal section showing the carriage in normal or lower case position; and 25 Fig. 2, a like view showing it in elevated or upper case position.

The latch 1 that engages the bracket 2 on a downward extension 3 of the shifting carriage has a hook 1^a that locks the carriage 30 in lowermost position. The means for shifting the carriage,—*i. e.* links 4, 5,—operate first to withdraw the latch and to then elevate the carriage as explained in the above mentioned patent. In the present invention, the latch performs the further function of supporting or locking the carriage in elevated position and to this end it is formed 35 with a rearwardly extending projection 1^b which as the carriage is lifted passes under the bracket 2 and supports the carriage in elevated position. Since means of adjusting this latch may be desirable under some con-

ditions provision for adjustment is made at its pivot. This may be effected satisfactorily and conveniently by providing an 45 eccentric adjustable pivot bolt 6. The mode of operation of the latch is clearly apparent from the drawing and further description is unnecessary.

50 I claim:

1. In a typewriting machine, the combination of a shifting platen frame, a pivoted latch engaging it for locking it in lowermost position and also for supporting it in uppermost position, means for disengaging the latch to permit the platen to rise, for shifting the platen and for reengaging the latch to support the platen in shifted position.

2. In a typewriting machine, the combination of a shifting platen frame, an adjustable latch engaging it for locking it in lowermost position and also for supporting it in uppermost position, means for disengaging the latch to permit the platen to 60 rise, for shifting the platen and for reengaging the latch to support the platen in shifted position.

3. In a typewriting machine, the combination of a shifting platen frame, a latch 70 having an eccentric adjustable pivot and engaging the platen frame for locking it in lowermost position and also for supporting it in uppermost position, means for disengaging the latch to permit the platen to 75 rise, for shifting the platen and for reengaging the latch to support the platen in shifted position.

In testimony whereof I have hereunto subscribed my name.

JAMES F. McBIRNEY.
